UNITED STATES PATENT OFFICE

172,321

PNEUMATIC BELLows

Donald C. Turner, Penfield, N. Y.

Application May 6, 1953, Serial No. 24,891

Term of patent 14 years

(Cl. D62—2)

To all whom it may concern:

Be it known that I, Donald C. Turner, a citizen of the United States of America and resident of the town of Penfield, in the county of Monroe and State of New York, have invented a new, original, and ornamental Design for a Pneumatic Bellows, of which the following is a specification, reference being had to the accompanying drawings, forming part hereof.

Fig. 1 is a plan view of a pneumatic bellows in compressed condition, showing my new design;

Fig. 2 is an edge view of the same, viewed from the side;

Fig. 3 is an edge view of the same, viewed from the front;

Fig. 4 is a view similar to Fig. 2 but with the parts in expanded condition; and

Fig. 5 is a fragmentary elevation of the rear end of the bellows in expanded condition.

I claim:

The ornamental design for a pneumatic bellows, substantially as shown.
